UNITED STATES PATENT OFFICE

165,405

BUILDING

George D. Tesch, Chicago, Ill.

Application September 5, 1950, Serial No. 12,063

Term of patent 14 years

(Cl. D13—1)

To all whom it may concern:

Be it known that I, George D. Tesch, a citizen of the United States of America, and resident of the city of Chicago, county of Cook, and State of Illinois, have invented a new, original, and ornamental Design for a Building, of which the following is a specification, reference being had to the accompanying drawing, forming a part thereof.

In the drawing:

Figure 1 is a top plan view of the building, showing my new design.

Fig. 2 is an elevational view as observed from the front of Fig. 1.

Fig. 3 is a transverse sectional view of the second floor.

Fig. 4 is an elevational view, as observed from the front of Fig. 3.

Fig. 5 is a transverse sectional view of the first floor.

The dominant features of my design reside in the portions shown in full lines.

I claim:

The ornamental design for a building, substantially as shown and described.

GEORGE D. TESCH.
